WILLIAM P. BROWN, OF WATERTOWN, NEW YORK.

Letters Patent No. 81,592, dated September 1, 1868.

IMPROVEMENT IN ADVERTISING SHOW-FRAMES.

The Schedule referred to in these Letters Patent and making part of the same.

TO ALL WHOM IT MAY CONCERN:

Be it known that I, WILLIAM P. BROWN, of Watertown, in the county of Jefferson, and State of New York, have invented a new and improved Advertising-Bulletin Frame; and I do hereby declare that the following is a full, clear, and exact description thereof, which will enable those skilled in the art to make and use the same, reference being had to the accompanying drawings, forming part of this specification, in which—

Figure 1 is a front view of my improved bulletin-frame.

Figure 2 is a back view of the same.

Figure 3 is a cross-section of the frame through the line $x\ x$, fig. 1.

Figure 4 is a similar section, in red color, showing certain modifications of the invention.

Similar letters of reference indicate corresponding parts.

The object of this invention is to provide a convenient and inexpensive means of publishing a number of business advertisements in the same frame.

It consists of a frame constructed with several devices, for the convenient insertion or removal of a number of advertisements, as the firm, styles, and nature of business, and addresses, and the like, whereby the same can be inserted, and displayed permanently in some public place, and so arranged that any one of the said advertisements can be readily removed, or substituted by other or different advertisements.

It consists of a frame, having an arched, angular, or other ornamental top, and provided with an inner removable frame, having sash-strips for holding several panes of glass.

The inner frame is further provided with a number of removable or hinged backs, corresponding in size and number to the panes, and which fit within the compartments of the sash and against the panes, thus holding them in place.

The fronts of these backs are provided with any suitable ornamentation, as a colored ground of paper, cloth, flock, or paint, either plain or figured, and the cards of advertisement, either printed or artistically executed by hand, are gummed or otherwise affixed upon the colored ground of the backs, which will thus display them through the panes when the backs are in place.

Removable blinds or shutters are also provided, for the protection of the glass from breakage during the night. The blinds are in two parts, and are held in place by a groove or projecting moulding, formed on the outer frame, in front of the glass, the lower and outer edges of the blinds fitting in the groove, and secured from removal by an eye-bolt and padlock, the said eye-bolt projecting from the sash so as to come between the proximate edges of the blinds.

Other devices, perfecting the whole, will be duly set forth in the following specific description.

In the accompanying drawings—

A is the outer frame, and

d the inner frame, which is removable when occasion requires.

This latter frame is crossed with sash-strips *a*, which are rabbeted to receive the edges of the glass panes, which panes are shown in green color at fig. 3.

B are the removable backs, and may be either hinged to the frame *d* by butts *m*, and secured by ordinary face-locks *l*, or may be separately removable from the frame, being confined by metal bars *e*, attached loosely to staples *f* in a strip, *h*, and reaching across the backs, as shown, to staples and padlocks *i*, on the frame *A*.

n n are the blinds, and are of wood.

o is the moulding, forming the groove in which they rest.

k is the eye-bolt, against which the blinds shut, and

p the padlock securing them.

The blinds are inserted by slipping their outer edges into the vertical part of the frame *A*, and then sliding downward, while the lower edges are entered in the bottom groove.

Having thus described my invention, what I claim as new, and desire to secure by Letters Patent, is—

The bulletin-frame, as constructed of the outer frame A and inner frame d, the latter divided by sash strips a, and provided with panes of glass and removable backs B, the frame A having mouldings and fastening devices, adapted to secure the shutters n, all arranged substantially as herein shown and described, for the purposes specified.

The above specification of my invention signed by me, this day of May, 1868.

WM. P. BROWN.
